[57] CLAIM

The ornamental design for a closure for a bowl or the like, substantially as shown.

DESCRIPTION

FIG. 1 is a top perspective view of a closure for a bowl or the like showing my new design;

FIG. 2 is a side elevational view thereof;

FIG. 3 is a top plan view thereof;

FIG. 4 is a bottom plan view thereof; and

FIG. 5 is an enlarged cross-sectional view thereof taken along line 5—5 of FIG. 2.

FIG. 1

FIG. 2

FIG. 3

FIG. 4

FIG. 5
